UNITED STATES PATENT OFFICE.

ELBRIDGE S. COLLEY, OF PORTLAND, MAINE, ASSIGNOR, BY DIRECT AND MESNE ASSIGNMENTS, TO THE COLLEY COMPANY, OF PORTLAND, MAINE, A CORPORATION OF MAINE.

HOISTING APPARATUS.

No. 878,040.

Specification of Letters Patent.

Patented Jan. 7, 1908.

Application filed February 17, 1906. Serial No. 301,545.

To all whom it may concern:

Be it known that I, ELBRIDGE S. COLLEY, a citizen of the United States of America, and a resident of Portland, county of Cumberland, State of Maine, have invented certain new and useful Improvements in Hoisting Apparatus, of which the following is a specification.

My invention relates to a hoisting device such as is used for unloading coal and the like from vessels and it is applicable to other forms as well.

The particular form of hoisting devices on which my invention is designed to be used is what is known as the "one man digger" used for discharging vessels loaded with coal and other like material in bulk. These "one man diggers" generally consist of a tower mounted on trucks and running on a track along the edge of the dock so that it may be accurately located with respect to the hatchways of the vessel. The tower is provided with a platform on which is placed a hoisting engine with two hoisting drums and a trolley engine and drum. The bucket is raised and lowered by ropes carried by the hoisting drums and running through a trolley which is movable on a horizontal boom and the motion of the trolley on this boom is controlled by the trolley engine and drum.

Both of the main drums and the trolley drum mentioned are provided with friction clutches controlled by clutch levers, the trolley drum is also provided with a friction band and lever. Thus it is necessary in the case of the "one man diggers" for one man to control the clutch lever of each of the three drums and the friction band of the trolley drum as well as the throttle valve of each engine, making six motions which must be controlled. This has hitherto been done by means of mechanical levers heavy and difficult to operate as it was necessary for the operator to stand at some distance from the engine to overlook the work.

The object of my present invention is to enable one man to easily control the main engine and hoisting drums and the trolley engine and drum and throttle valves and I accomplish this object by a system of air control by which each of the friction levers and other parts is operated by an air cylinder containing a piston and piston rod with mechanism connecting with these parts, a compressed air tank supplying pressure to

the air cylinder through suitable supply pipes. The supply pipes have controlling valves which can be located at any convenient point to overlook the work, each valve being preferably arranged to control two lines of pipe by means of a single lever so that the operator can control the four motions by the use of his two hands and the throttles may be controlled by the feet as now done by mechanical levers.

In the accompanying drawing I have shown means for controlling the clutch levers of one of the main hoisting drums and the trolley drum, but in practice this controlling valve is duplicated for controlling other parts as hereinafter stated.

In the drawing:—Figure 1 is a general side elevation of the main hoisting engine and the trolley engine, with the respective drums and the controlling valve, air tank and connections, Fig. 2 is a vertical section through the controlling valve taken on the line $z z$ of Fig. 3. Fig. 3 is a horizontal section on the line $x x$ of Fig. 2. Fig. 4 is a section on $y y$ of Fig. 2 and Fig. 5 is a section on $z z$ of Fig. 2.

A, represents the main hoisting engine, B, the trolley engine, A' one of the main hoisting drums, B' the trolley drum, a the clutch lever of the main drum and b the clutch lever of the trolley drum. These parts are all common and well known in this class of devices and need no further description.

Each of the clutch levers a and b is controlled by an air cylinder and piston with connecting mechanism. The air cylinder c contains a piston c^3 and piston rod c^2 the outer end of which is in turn connected by means of an elbow lever a^2 and a pitman a^1 with the clutch lever a .

Air pressure is applied to the cylinder beneath the piston by an air pipe d and the application of the air acts to apply the clutch. The piston is returned to its normal position and the clutch released by a spiral spring c' which surrounds the piston rod and tends to depress the piston. The air cylinder e is in like manner connected with the clutch lever b by means of its piston rod e' , elbow lever e^2 and pitman e^3 and it is supplied with air through the pipe g .

A suitable compressed air tank f is supplied with compressed air from any suitable source and air is taken from the tank through an air tank pipe f' . The air in its passage through the pipe f' to the supply pipes d and

g passes through a suitable controlling valve, the one herein shown being well adapted for the purpose. The valve V is placed at a convenient point for viewing the work and is connected with the tank and with the operating cylinders.

As here shown, the valve is made up of two open ended cylindrical sections H and J with double walls which leave annular chambers between the inner and outer walls. They are placed end to end axially in line with each other and they have between the abutting ends the diaphragm i and at the top and bottom are end plates o' and o respectively. The valve casing is held together by bolts p which pass through the upper and lower end plates and clamp all the parts together. In the cylindrical bore of one casing is a piston valve controlling the air supply to one of the cylinders c and e and in the other casing is a rotary valve controlling the supply to the other operating cylinder.

As here shown, the lower casing contains the piston valve and controls the main friction. In the center of the casing H is a piston valve having a reduced central cylindrical portion h and enlarged piston ends h' and h''. The lower end h' controls the ports h⁶ and h³ which communicate with the annular chambers h⁷ (Fig. 5) and thence to the screw threaded outlet h⁸ where an exhaust pipe is connected. Opposite the central portion of the valve is the port h⁵ connecting directly with the threaded opening d' from which the pipe d leads to the operating cylinder c. The upper portion of the valve h² covers the ports h⁴ h⁴ connecting with the opening f³ from which the pipe f² leads to the supply tank. The valve stem v' passes up and out at the top of the cylinder. Thus when the valve is in its central position as shown in Fig. 2 both the tank connection and the exhaust are shut off. When it is raised, the ports h⁴ are opened into the central space in the valve and the air passes through the valve and thence out of the opening d' to the pipe d and to the cylinder c.

When the valve is depressed below its central or neutral position the ports h³, h⁶ are opened and ports h⁴ closed and the opening d' is connected through the valve with the annular space h⁷ and thence out through the opening h⁸ (Fig. 5) to the open air, whereby the working pressure in the cylinder is exhausted and the clutch lever released. Thus when the valve is raised the air is turned into the cylinder and the clutch thrown in and when it is depressed the operating cylinder is exhausted and the clutch released.

The trolley clutch is controlled by the rotary valve k which is located above the diaphragm i. The annular space surrounding the valve proper (Fig. 3) is divided into three parts by partitions j³, j⁴ and j⁵ one section having an outlet at the threaded opening g con-

nected with pipe g which controls the trolley operating cylinder e, one of the spaces connects with the opening f¹³ and thence through pipe f² to the tank supply and the third space connecting with the exhaust opening j'. The first of these spaces has a port 6, the second a port 7 and the third a port 5 opening through the central wall. A partition k³ divides the valve k into two chambers horizontally k⁶ and k⁷. In the walls of the chamber k⁶ are ports 2 and 3 which register respectively with the ports 6 and 7 when the valve is turned to the left of its neutral position but register with neither when the valve is central. Thus, when the valve is turned to the left the ports 2 and 6 register as do the ports 3 and 7, thus allowing the air to pass from the tank opening f³ through the valve to the trolley cylinder opening g'. The chamber k⁷ has two ports 1 and 4 in its walls.

To exhaust the operating cylinder, the valve is turned to the right, bringing a port 1 to register with port 6 and port 4 to register with port 5. There is thus formed a passage through the valve from the cylinder opening g' to the exhaust, the tank pressure being meanwhile shut off. It will thus be seen that when the valve is turned to the left the air pressure is turned on the operating cylinder and the trolley clutch is applied and when the valve is turned to the right it is released and the air opened to the exhaust.

The stem k' of the valve passes up through the upper plate o' and above the plate it is squared and receives an arm m by which it is turned. A nut k² on the extreme upper end of the valve stem holds the arm in position. The arm m serves as a pivoting support for the lever v which raises and lowers the valve stem v' of the valve h this valve stem passing centrally up through the valve k and its stem k'. The end of the arm m is turned up to form a pivoting support to the lever v. It will be seen that both valves may be controlled by the lever v which by a vertical motion can be made to raise and lower the lower piston valve and by a swinging motion it will turn the arm m and the valve k.

I have here shown means for operating the clutch levers of the main drum and the trolley drum but in practice, the controlling valve is duplicated so that the operator operates each with one hand. With one hand he operates as here shown one of the main clutch levers by the piston valve and the trolley clutch lever with the upper rotary valve, while with the other hand he operates the clutch lever of the other main drum by the other piston valve and the band friction on the trolley drum by the other rotary valve.

The apparatus has the advantage of being located at any desirable point to overlook the work, it is easy for the operator to handle it is quick and sensitive in its action and by its use it reduces the time for unloading a

vessel, an important consideration, and it is perfectly safe.

I claim:

- 5 1. In a hoisting device, the combination with the main hoisting drum and auxiliary hoisting drum of a friction for each drum, an air operated device for operating each of said frictions, a compressed air reservoir, supply pipes connecting said reservoir with each of
- 10 10 said air operated devices, double acting control valve through which both lines of pipe pass and an operating lever for said valve for controlling both lines of pipe and both frictions.
- 15 2. In a hoisting device of the class described, the combination with the clutch le-

vers of the main hoisting drum and the trolley drum, of an air cylinder for each lever, a piston therein, a piston rod for said piston operatively connected with the clutch lever, 20 a compressed air reservoir, supply pipes connecting said reservoir with said air cylinders and a double acting controlling valve through which both lines of pipes pass said valve having an operating lever for controlling both 25 lines of pipe and the pressure on both air cylinders.
